UNITED STATES PATENT OFFICE

169,012

COMBINED DESK, SEAT, AND BLACKBOARD

Louis T. Musacco, San Gabriel, Calif.

Application May 22, 1952, Serial No. 19,828

Term of patent 7 years

(Cl. D33—11)

To all whom it may concern:

Be it known that I, Louis T. Musacco, a citizen of the United States, residing at San Gabriel, in the county of Los Angeles and State of California, have invented a new, original, and ornamental Design for a Combined Desk, Seat, and Blackboard, of which the following is a specification, reference being had to the accompanying drawing, forming part thereof.

Figure 1 is a rear perspective view of a combined desk, seat and blackboard, showing my new design, and

Figure 2 is a side perspective view thereof.

I claim:

The ornamental design for a combined desk, seat, and blackboard, as shown.

LOUIS T. MUSACCO.
